UNITED STATES PATENT OFFICE.

JULIUS SCHNEIDER, OF NEW YORK, N. Y.

NEEDLE-THREADER.

1,144,504.

Specification of Letters Patent. Patented June 29, 1915.

Application filed February 16, 1915. Serial No. 8,460.

To all whom it may concern:

Be it known that I, JULIUS SCHNEIDER, a citizen of Servia, and a resident of New York city, in the county and State of New York, have invented certain new and useful Improvements in Needle-Threaders, of which the following is a specification.

This invention relates to an implement of novel construction, by means of which needles may be threaded in a quick and simple manner.

In the accompanying drawing, Figure 1 is a perspective view of a needle threader embodying my invention, showing the same in use; Fig. 2 is a detail of the grip, before being bent; Fig. 3 a side view partly in section of the implement, and Fig. 4 a longitudinal section thereof.

The device comprises essentially, a resilient filament formed preferably of very thin wire, and bent into the form of a loop. This loop is provided with a doubled narrow front section or nose 1 adapted to be readily passed through the eye of a needle. Back of this front section, the two members of the loop diverge from each other as at 2 to form an expanded section or threading opening 3 therebetween. The rear end of each diverging or convex section 2, is provided with one or more corrugations 4, constituting a heel or abutment. The handle 5 of the device is provided with a flat shank 6, having a small perforation 7 located some distance back of its free end. In assembling the parts, the loop is thrust with its nose and convex section through this perforation, until its heel strikes the body of the

shank. That portion of the shank that extends beyond perforation 7 is then doubled against the body of the shank, to form a 40 flange 8, between which and the unbent portion of the shank, the heel is securely confined. Finally, a small protuberance 9 is thrown up from the body of the shank, by means of a punch, which protuberance 45 engages either one of the heel corrugations, and thus securely locks the loop to the grip.

In use the nose 1 is inserted into the eye of a needle 10, and then the entire loop is pushed back through said eye, during which 50 operation, the convex loop sections 2, will first contract and then expand into their normal position. The thread 11 is passed through the expanded section 3 of the loop, and the needle is drawn forward to entirely clear the loop as well as the doubled end 12 of the thread. In this way the needle will be threaded in a quick and handy manner without unduly straining the eyes of the operator. 55

I claim:

In a needle threader a grip having a doubled apertured shank and a protuberance on the shank, combined with a resilient looped filament extending through the shank-aperture and having a contracted nose, an expanded section back of the nose and a corrugated heel back of the expanded section, which heel is engaged by the grip-protuberance. 65
